UNITED STATES PATENT OFFICE.

HENRY U. SPENCE, OF PAINESVILLE, OHIO.

LUBRICATING SYSTEM.

1,390,393.

Specification of Letters Patent. Patented Sept. 13, 1921.

Application filed December 18, 1920. Serial No. 431,633.

To all whom it may concern:

Be it known that I, HENRY U. SPENCE, a citizen of the United States, residing at Painesville, in the county of Lake and State of Ohio, have invented certain new and useful Improvements in Lubricating Systems, of which the following is a specification.

This invention pertains to lubricating systems, and has to do more particularly with 10 the so-called "splash systems" employed for lubricating the cranks, and the pistons and cylinders of automobile engines of the internal combustion type.

In systems where the splash action is depended upon to effect lubrication it frequently occurs that some one or more of the cylinders and its allied parts will be over lubricated and that others will be under lubricated. This is not only incidental to the 20 construction employed but is likewise due at times to the position of the machine when upon the road; thus when going down grade the oil is apt to over accumulate in the forward oil holding pocket (or pockets) and 25 when going up grade such pockets may not receive sufficient oil. Over lubrication leads to fouled spark plugs and the deposition of carbon on the cylinder head due to the working of the oil past the piston rings.

The main object of the present invention is to overcome these difficulties and to insure the proper quantity of oil being maintained in each pocket throughout the series and to so arrange the parts that an even flow of oil to 30 each pocket will be had, this irrespective of the engine speed, or whether the machine is traveling up or down grade, or whether it is running in a sidewise tilted position upon a crowned road. With this and further objects and advantages in view as will herein-after appear, reference will be had to the annexed drawings wherein a preferred embodiment of the invention is shown, the same being illustrated in connection with the 35 housing of a Ford car though as will be appreciated the invention is of general application and may be utilized in connection with any number of cranks.

Figure 1 is a longitudinal sectional view 40 of a portion of an engine housing and under bonnet with the oil pan of my invention applied thereto.

Fig. 2 a plan view of the pan.

Fig. 3 a sectional view taken on the line 45 III-III of Fig. 2.

Fig. 4 a longitudinal sectional view taken on the line IV-IV of Fig. 2.

Fig. 5 a transverse sectional view on the line V-V of Fig. 2.

Fig. 6 a like view on the line VI-VI. 60

Fig. 7 a perspective view of one of the valves or gates employed to regulate the inflow of oil to the pockets of the pan.

Fig. 8 a similar view showing the preferred formation of the floor and wall at one 65 end of the opening leading to an oil holding pocket, and

Fig. 9 a sectional elevation of such floor and wall elements with the gate positioned 70 with reference thereto.

In the drawings, 1 denotes the crank case and 2 the under bonnet having an opening in the bottom thereof below the cranks 3, 4 and 5, and connecting rods adapted to be closed by a pan about to be described. The 75 fourth crank designated by 6 dips into a depression 7 formed at the forward end of the magneto and fly wheel housing 8 which as will be understood is filled with oil to a greater or less extent, the oil being splashed 80 about by the magneto and wheel.

The pan for closing the opening in the under bonnet 2 is designated generally by 9 and is secured in place with machine screws 10 which pass through the rim or edge of 85 the pan, through openings in the bonnet and into U-shaped clamping plates 11 and 12. The latter is preferably of the form best shown in Figs. 1 to 3 and is provided with two arched elements or sections 13 forming 90 passages thereunder to prevent the holding back of the oil flow and the building up of the oil level in the pan. In other words the openings allow the oil to flow back into the magneto housing beneath the clamping element 95 instead of over it and thus the oil level in the pan is reduced to that extent.

The pan is formed with three pockets 14, 15 and 16 located in line with the cranks 3, 4 and 5, respectively, and inasmuch as the 100 formation of the pockets and allied parts are the same a description of one will suffice for all and the same reference numerals will be applied to each of them.

The oil for lubrication is circulated from 105 the housing 8 into the forward end of the pan 9 from which it flows back to the housing. This being usual in the Ford machine, the means for accomplishing it is not shown in the drawings. 110

The bottom of the pan is formed upon two levels or planes designated respectively by 17 and 18, the upper level 17 merging into the lower one 18 through sloping walls 5 19, which lie at an angle to the longitudinal axis of the pan.

Each pocket is provided with an upstanding surrounding wall 20 which rises above the bottom of the pan, and an oil inlet or 10 opening 21 is formed therein at the forward side of the pocket.

The inclined sloping wall 19 forward of the pocket extends toward the opening and merges into an inwardly inclined face 22 15 (see Figs. 8 and 9) formed adjacent the bottom of the wall 20 at one end of the opening 21, the upper margin or edge of the face terminating in a flat 23 which lies in a level slightly above the upper level 17 20 of the pan bottom. The wall 20 at this end of the opening is provided with an inclined face 24, said face and the face 22 co-operating 25 with a gate 25 to regulate the inflow of oil from the pan to the pocket as will presently appear.

The gate is of the form best shown in Fig. 7 and is secured upon the upper end of a rod 26 mounted for rotation in a bearing 27 (provided with a packing gland 27') 30 formed in the pan bottom adjacent the end of opening 21. The stem or rod 26 is bent laterally forming a handle 28 provided with a tooth 29 adapted to co-act with a rack 30 formed on the bottom of the pan to hold the valve in its adjusted position.

A by-pass or conduit 31 is formed under each pan adjacent that end where the gate is located so that the oil may flow freely from the forward end of the pan to the rear 40 thereof, suitable return deflecting walls 32, being provided at the outlet ends of the conduits (except at the last pocket 16) to cause the oil to flow across the lower pan level 18 toward the pocket opening 21 rather 45 than to flow directly to the next by-pass.

A second series of conduits or by-passes 33 is provided at the opposite end of the pockets, said conduits coming into operation more particularly when the machine is 50 tipped sidewise when traveling on a crowned road.

An upstanding wall 34 may be provided between the pockets 14 and 15 to prevent the oil being splashed from one pan into the other. Pans 15 and 16 being more widely spaced no wall between them will be found necessary.

In operation the oil as above stated is 60 passed from the magneto and fly-wheel housing 8 into the forward end of the pan and thence it travels rearwardly over the pan back to the housing. During such flow the pockets become filled to the desired extent, the inflow to each pocket being regulated by 65 the gate to insure a supply equal to that

splashed out by the bearings, as they pass into and through the oil in the pockets.

This inflow may be nicely regulated by the gates. As the gate is swung toward its closed position it moves past the inclined 71 face 22 and thus gradually narrows the space through which the oil may flow. As it is moved farther inward its end coacts with the inclined wall 24 and further gradually cuts down the oil inflow. Such inflow may be 76 almost entirely cut off by a complete closure of the gate, its end at such time abutting the inner upstanding edge of the face 24.

Inasmuch as pocket 14 is apt under the construction commonly employed to receive 80 too much oil the gate therefor will be all but closed; gate for pocket 15 will be adjusted to be open wider, while gate for pocket 16 will be opened still farther, but this adjustment may be varied to suit each 85 individual motor.

Once the gates are brought to their proper adjusted positions they may remain so as the oil level in each pocket will be maintained substantially constant under all conditions of operation. The rate at which the oil enters the forward end of the pan increases with the speed of the motor, and as the oil cannot flow through the by-passes and under the clamping plate at 13, under 95 such conditions at a sufficient rate, its level outside the gates 25 is raised and a greater quantity passes through them and into the pockets. At the same time the increased engine speed results in the oil being splashed 100 out of the pockets more rapidly, so that a constant oil level may be maintained under varying engine speeds.

What is claimed is:—

1. In a splash lubricating system, the 105 combination with the under bonnet of a crank case; of a pan supported thereby, said pan having a plurality of pockets formed therein in position to be entered by the connecting rods; a gate for each pocket controlling an opening in the side wall of each 110 pocket through which the oil may enter; and a by-pass located adjacent each pocket for permitting the flow of oil from one end of the pan to the other.

2. In a splash lubricating system, the combination of the under bonnet of a crank case; a pan supported thereby and in which the oil is adapted to flow from one end to the other; a plurality of pockets formed therein 120 in position to be entered by the connecting rods, each pocket having upstanding walls rising above the body of the pan with an oil inlet opening formed in the forward wall of each pan; a gate for each of said 125 openings; and means for independently regulating the position of each gate.

3. In a splash lubricating system, the combination of the under bonnet of a crank case; a pan supported thereby and in which 130

the oil is adapted to flow from one end to the other; a plurality of pockets formed therein in position to be entered by the connecting rods, each pocket having an opening 5 in its side wall; and means for regulating the flow of oil into the pockets through said openings as it passes along the pan.

4. In a lubricating system of the splash type, the combination of a pan over which the oil flows from one end to the other; a plurality of pockets formed in the pan in position to be entered by the connecting rods and to receive oil from the pan as it flows over the same; and means for maintaining the level of the oil in each of the pockets at a substantially constant level.

5. In a lubricating system of the splash type, the combination of a pan over which the oil flows from one end to the other; a plurality of pockets formed in the pan in position to be entered by the connecting rods and to receive oil from the pan as it flows over the same; and means for regulating the amount of oil which may pass into each 25 pocket and by-passing the remainder past said pockets to the discharge end of the pan.

6. In a lubricating system of the splash type, the combination of a pan over which the oil is circulated from one end to the other; a series of pockets formed therein 30 and having upstanding walls projecting above the pan bottom, the wall of each pocket having an opening therein for the entrance of oil to the pocket; an adjustable gate for each opening; and means co-operating with the gates to secure a ready control of the inflow of oil past the same.

7. In a lubricating system of the splash type, the combination of a pan over which the oil is circulated from one end to the other; a series of pockets formed therein 40 and having upstanding walls projecting above the pan bottom, the wall of each pocket having an opening therein for the entrance of oil to the pocket; an adjustable gate for each opening; means co-operating with the gates to secure a ready control 45 of the inflow of oil past the same; and by-passes for the oil extending around the pockets.

8. In a lubricating system of the splash type, the combination of a pan over which the oil is circulated from one end to the other; a series of pockets formed therein, 55 each pocket having upstanding walls with an opening in one side, the wall at one end of the opening being beveled or inclined; an outwardly projecting member located at the base of said edge and provided with 60 an outwardly inclined face; a gate adapted to co-operate with said member and the inclined end aforesaid; and means for controlling the position of the gate.

9. In a lubricating system of the splash 65 type, the combination of a pan over which

the oil flows, the upper face whereof is divided into two levels extending lengthwise of the pan; a plurality of pockets the walls whereof extend upwardly above said pan bottom, the wall of each being provided with an intake opening for the oil which opens into the lower level of the pan; a gate for each opening; and means for adjusting and holding said gate.

10. In a lubricating system of the splash type, a pan over which the oil is caused to flow; a series of pockets carried by the pan, each pocket having an opening in its side wall for the entrance of oil; a gate for controlling said opening; a by-pass extending around each pocket; and a return deflecting wall extending up from the pan adjacent the discharge ends of the by-passes other than the last one.

11. In a lubricating system of the splash type, the combination of the under bonnet of an engine housing, said bonnet having an opening therein; a pan underlying the bonnet; a clamping plate resting on the inner face of the bonnet, said plate having at 90 least one arched member located adjacent the discharge end of the pan; means for securing the pan, said plate, and the bonnet together; and a plurality of pockets carried by the pan and into which the engine cranks 95 may dip.

12. In a lubricating system of the splash type, the combination of a pan over which the oil is caused to flow from one end to the other; a series of pockets carried thereby, 100 each pocket having a gate controlled opening in line with the flow of oil; and a by-pass extending around each end of each pocket.

13. In a lubricating system of the splash type, the combination of a pan over which the oil is caused to flow from one end to the other; a series of pockets carried thereby, 105 each pocket having a gate controlled opening in line with the flow of oil; a by-pass extending around each end of each pocket; 110 and means for causing a deflection in the flow of oil passing from the by-passes toward the gate controlled opening in the next succeeding pocket.

14. In a lubricating system of the splash type, the combination of a pan over which the oil is caused to flow from one end to the other; a series of pockets carried thereby, 115 the two pockets at the forward end of the pan being more closely spaced than the other; a rib or partition extending upwardly from the pan between said closely spaced pockets whereby the oil splashed from one will be precluded from directly passing over into the other; and means for controlling 120 the regulation of the supply of oil passing into each pocket.

15. In a lubricating system of the splash type, the combination of a pan over which the oil is caused to flow from one end to the 130

other; a series of pockets carried thereby and into which the connecting rod dips; and means susceptible of manual adjustment from without the pan for maintaining the oil in each of the pockets at a substantially constant level.

16. In a lubricating system of the splash type, the combination of a pan over which the oil flows from one end to the other; a plurality of pockets in the pan in position to be entered by the connecting rods of an engine, said pockets being substantially closed off from the flow of oil in the pan except for an opening leading respectively from each of said pockets to the pan, said openings restricting and controlling the amount of oil which may enter each of said pockets; and a by-pass around each pocket.

17. In a splash lubricating system, the combination of an under bonnet of a crank case; a pan supported thereby, over which the oil is adapted to be circulated from one end to the other; a plurality of pockets formed therein in position to be entered by the connecting rods of an engine, said 2 pockets being substantially closed off by their walls from the flow of oil in the pan except for an opening formed respectively in each of said pockets and leading to the pan, said openings restricting and controlling 3 the amount of oil which may enter each pocket.

In testimony whereof I have signed my name to this specification.

HENRY U. SPENCE.
